UNITED STATES PATENT OFFICE.

WILLIAM C. KOCH, OF ST. PAUL, MINNESOTA, ASSIGNOR TO TWIN CITY BRICK COMPANY, OF ST. PAUL, MINNESOTA, A CORPORATION OF MINNESOTA.

CARTON FOR SHIPPING SAMPLE BRICK.

Application filed September 29, 1921. Serial No. 504,178.

To all whom it may concern:

Be it known that I, WILLIAM C. KOCH, a citizen of the United States, residing at St. Paul, in the county of Ramsey and State of Minnesota, have invented certain new and useful Improvements in Cartons for Shipping Sample Brick, of which the following is a specification.

This invention relates to cartons for shipping samples of brick laid up to represent a section of wall to render it attractive, the object of the invention being to provide a container which can be made of light material such as paper board, which ordinarily is not sufficiently strong for shipping merchandise of this character.

To this end, the invention consists in the construction, combination and arrangement of parts hereinafter described and claimed.

20 In the accompanying drawings:

Figure 1 is a perspective view of a carton embodying my invention.

Figure 2 is a perspective view of the same showing the walls of the carton unfolded 25 and the arranged brick tied to the bottom thereof, and

Figure 3 is a perspective view of strips arranged to represent the binder material between the bricks.

30 In the drawings, A designates the carton, preferably made of paper board, B the sample brick and C the binder element between the brick.

The shell comprises a floor or bottom 1, 35 upon which rest the brick B and walls 2 formed with flaps 3 which swing about the line of fold 4, and side walls 5 having flaps 6 which swing about the line of fold 7. As shown, in Figure 1, the end walls are first 40 positioned to embrace the brick, and the side walls then folded over the end walls, thus forming a compact package which may be suitably bound or wrapped for shipment by means not shown.

45 Between the bricks are the horizontal strips 8, to represent the horizontal mortar joints, the vertical butt joint being represented by the short strips 9.

The long strips 8 serve also as reinforcing bars to strengthen the carton lengthwise 50 against being flexed by the weight of the

brick which without these would be too weak to sustain the brick.

The displayed upper face of the brick is of full size but the thickness is shown reduced to conserve weight.

At the base of the side walls are the openings 10, through which pass the cords 11, the latter extending over the outside of the bottom 1, and transversely over the bricks, 60 and being suitably joined together so as to be readily untied when desired. As shown, each row consists of a full length brick and a half brick, the vertical joints alternating with each row, the openings 10 being located, so that the strings will bisect the half bricks and thereby firmly bind the assembled bricks together. Thus, the bricks are tied to the floor of the carton and firmly bound together as a unit.

In use, when it is desired to view the contents, the walls are unfolded, and the strings preferably untied, to obviate a note of discord in the general appearance.

Thus, I secure a compact package of brick 75 representing a rectangular section of wall, loosely assembled on the bottom of the carton, but capable of being readily bound firmly together to form with the carton a 80 unitary package.

I claim:

A sample package, comprising a foldable carton, formed with folding side and end walls, and side walls having openings at their base, each of said walls having a folding flap, said flap forming collectively when folded a closure for the carton, and a plurality of loosely assembled brick arranged to represent a section of wall within the carton, said wall including loosely assembled strips to represent the horizontal and vertical mortar joints between the bricks, and readily detachable tying means extending transversely of the bricks around the latter, and through said openings in the 90 side walls and across the bottom of the carton, whereby to tie the bricks and carton firmly together to form a unitary package.

In testimony whereof I affix my signature. 100

WILLIAM C. KOCH.
